(57) **CLAIM**

What is claimed is the ornamental design for, a wheel for an automobile, as shown and described.

DESCRIPTION

FIG. 1 is a front elevation view of a wheel for an automobile, showing our new design;

FIG. 2 is a top plan view thereof;

FIG. 3 is a right side elevation view thereof;

FIG. 4 is a perspective view thereof; and,

FIG. 5 is a cross sectional view thereof taken along line V—V in FIG. 1.

The broken line showing of environment is for illustrative purposes only and forms no part of the claimed design.
